UNITED STATES PATENT OFFICE.

GEORGE E. TUCK, HERBERT DORN, AND JAMES STEINSON, OF RIDGWAY, IOWA.

IMPROVEMENT IN STACK-COVERS.

Specification forming part of Letters Patent No. **179,976**, dated July 18, 1876; application filed March 21, 1876.

To all whom it may concern:

Be it known that we, GEORGE E. TUCK, HERBERT DORN, and JAMES STEINSON, of Ridgway, Winneshiek county, Iowa, have invented a new and Improved Stack-Cover, of which the following is a specification:

The invention consists in a conical stack-cover, provided with a lifting-ring at its apex, as and for the purpose more particularly described hereinafter.

Figure 1 is a sectional elevation of our improved stack-cover, taken on line *x x*, Fig. 2, and Fig. 2 is a top view.

Similar letters of reference indicate corresponding parts.

A is the cap of canvas or other approved material, constructed in conical form, and having a rope or cord, B, around the base, with rings C on it for hitching on the stay-ropes to keep the cap in place, and stay the stack against the wind.

The cap may be made of water-proof material; but probably ordinary canvas, with a coating of water-proof paint, will generally be used.

D is a ring or loop, placed at the apex of the conical cap, so that the latter may be conveniently lifted with a rod or pole having a fork at one end, and then dropped over the grain or hay without the trouble of climbing, by ladder or otherwise, upon the stack.

What we claim is—

A stack-cover, of conical form, and having a lift-ring, D, at the apex thereof, substantially as and for the purpose specified.

GEORGE E. TUCK,
HERBERT DORN,
JAMES STEINSON.
